Primary Examiner — Jack Reickel(74) *Attorney, Agent, or Firm* — NSIP Law**CLAIM**

We claim the ornamental design for a display screen or portion thereof with graphical user interface, as shown and described.

DESCRIPTION

The sole FIGURE is a front view of a display screen or portion thereof with graphical user interface showing our new design.

The outermost broken line in the FIGURE represents a display screen or portion thereof that forms no part of the claimed design. The remaining broken lines in the FIGURE depict portions of the graphical user interface that form no part of the claimed design. The grayscale tones shown in the FIGURE illustrate a contrast in appearance.
